UNITED STATES PATENT OFFICE.

AUGUST BURGERT, OF MÜLHAUSEN, GERMANY, ASSIGNOR TO ELSÄSSISCHE MASCHINENBAU-GESELLSCHAFT, OF MÜLHAUSEN, GERMANY.

COMBINED PRINTING-MACHINE FOR TEXT AND INTAGLIO FINE PRINTING.

1,105,482.

Specification of Letters Patent.

Patented July 28, 1914.

Application filed July 17, 1913. Serial No. 779,564.

To all whom it may concern:

Be it known that I, AUGUST BURGERT, a subject of the German Emperor, residing at Mülhausen, in the Province of Alsace-Lorraine, Germany, have invented a new and useful Improvement in Combined Printing-Machines for Text and Intaglio Fine Printing, of which the following is a specification.

10 My present invention relates to an improvement in combined intaglio printing together with ordinary relief printing machines.

In contradistinction to machines for text and illustration printing for relief printing, the fine and counter printing machine for intaglio printing, as it has hitherto been constructed is composed of two practically independent machines, which are rigidly connected to one another by means of common supports or by being screwed together. This mode of construction especially applies to the so called Mertens intaglio printing machines as hitherto produced. The paper web was hitherto arranged to pass through the mechanisms thus interconnected for intaglio printing and was then provided with text relief printing away from the two intaglio printing machines and cut and folded.

30 The object of my present invention is a composite fine and counter printing mechanism for intaglio printing so combined with a rotary relief printing machine that the text printing mechanism (preferably 35 provided with cutting and folding apparatus) is interpolated between the fine printing mechanism and the counter printing mechanism of the intaglio printing machine.

Instead of building the text relief printing machine between two intaglio printing machines adapted to print on one side only, there can of course be provided on each side of the relief printing machine also a fine and counter printing mechanism for intaglio printing or for multiple color intaglio printing. The advantages of an arrangement of this kind are numerous. Especially I may mention: 1. There is a very considerable shortening of the working length of the 50 paper web. 2. The carrying of the paper web along the floor between the intaglio and the relief printing mechanism is avoided. 3. There is a greatly improved oversight of the operation because from the folding apparatus both the intaglio and the relief

printing mechanisms can be watched during the printing. 4. There is a shortening of the space required by the machines. 5. A considerable simplification of the driving. By thus constructing the fine and counter printing mechanism or intaglio and relief printing there is created a special type of machine which is new of its kind and neither known hitherto nor constructed in this manner. Through the organic union of the machines into a unitary structure, a new machine is produced which operates more compactly, firmly and surely and affords the most exact register.

As is well known hitherto intaglio printing machines have been coupled to the relief printing machines by means of special devices. In such couplings, there may easily occur a mistake of the mounter so that either the frames of the intaglio printing mechanism or of the rotary machine were not placed mathematically exactly level and at the same angle or were badly foundationed. Even the very slightest errors of this kind produce irregularities often very difficult to overcome (such as the formation of folds, tearing of the paper web and so forth). A further occasion of disturbances occur through the failure of one of the two motors requisite, because hitherto in most cases a special motor has been necessary for the intaglio printing work and another for the driving of the relief printing machine. The new machine on the other hand works with a single motor. Finally, the advantage above stated of more compact construction enables a much smaller space to be utilized.

The invention is illustrated diagrammatically in the accompanying drawing, in which—

Figure 1 shows an elevation and Fig. 2 a plan view of the new machine:

In these figures, A and B denote the supporting legs on which are supported intaglio printing cylinders, C and D, E and F the elastic intermediate rolls, G and H the pressure cylinders, J, K and L the cutting mechanism, forming part of the rotary relief printing machine, M and N the distributing mechanism, O, P, Q, R the form and impression cylinders of the text relief printing machine, S the paper web, T, T, T the paper guide rolls, U the driving motor, V and W the parallel arms of the frames of the machine.

The operation of the machine is briefly as follows: The paper web passes from S between the rolls E, C over the various guide rolls T to the intaglio printing machine B, 5 passing between the intaglio printing form cylinder D and the elastic intermediate roll F. From this point it passes into the relief printing rotary machine, then partially around the relief printing cylinders P and 10 Q and to the cutting apparatus J, K, L and is then piled upon the table N after passing through the mechanism M.

What I claim is:

In a rotary printing machine, a frame 15 comprising supporting legs and parallel upper arms, a web supply roll supported on the parallel arms adjacent one end thereof, intaglio printing cylinders operating adjacent the respective ends of the frame, and impres-

sion cylinders coöperating therewith, said 20 printing cylinders operating below the plane of the parallel arms, guide cylinders supported by the frame, a series of relief printing cylinders supported intermediate the length of the parallel arms, and impression 25 cylinders coöperating therewith, cutting means supported under the series of relief printing cylinders for severing the web into sheets, and means for operating the cylinders, whereby the printing cylinders print 30 on both sides of the web.

In testimony whereof I have signed my name to this specification in the presence of two subscribing witnesses.

AUGUST BURGERT.
